UNITED STATES PATENT OFFICE.

SAMUEL HERBERT BEHRENS, OF STAMFORD HILL, LONDON, ENGLAND.

DESIGN FOR A CIGARETTE-CASE.

48,925.

Specification for Design.

Patented Apr. 25, 1916.

Application filed December 4, 1915. Serial No. 65,145. Term of patent 3½ years.

To all whom it may concern:

Be it known that I, SAMUEL HERBERT BEHRENS, a subject of the King of Great Britain and Ireland, residing at 91 Holmleigh Road, Stamford Hill, in the county of London, England, have invented a new, original, and ornamental Design for a Cigarette-Case, of which the following is a specification, reference being had to the accompanying drawing, forming part thereof, in which—case, showing my new design, and Fig. 2 an edge view.

I claim:

The ornamental design for a cigarette case as shown.

In testimony whereof I affix my signature in presence of two witnesses.

SAMUEL HERBERT BEHRENS.

Witnesses:

A. J. CRAIG,
J. TYNDALL.
